United States Patent Office

Des. 222,186
Patented Oct. 5, 1971

222,186

MAIL CHEST

George A. Stephen, Jr., Mount Prospect, Ill., assignor to
Weber-Stephen Products Co., Arlington Heights, Cook
County, Ill.

Filed July 27, 1970, Ser. No. 24,134

Term of patent 14 years

Int. Cl. D31

U.S. Cl. D74—9

Fig. 1.

Fig. 3.

Fig. 2.

FIG. 1 is a front perspective view showing my new design for a mail chest, the unshown back being plain and unornamented.

FIG. 2 is a perspective view showing my new design for a mail chest with the door slightly opened; and,

FIG. 3 is a side elevational view of my new design, the opposite side being a mirror image of the illustrated side.

I claim:

The ornamental design for mail chest, substantially as shown and described.
